UNITED STATES PATENT OFFICE.

EMERSON O. McLAUGHLIN, OF MOOREFIELD, NEBRASKA.

ROLLER ENSILAGE-PACKER.

1,109,443.

Specification of Letters Patent. Patented Sept. 1, 1914.

Application filed May 21, 1914. Serial No. 839,950.

To all whom it may concern:

Be it known that I, EMERSON O. McLAUGHLIN, citizen of the United States, residing at Moorefield, in the county of Frontier and State of Nebraska, have invented certain new and useful Improvements in Roller Ensilage-Packers, of which the following is a specification.

The present invention relates to certain new and useful improvements in ensilage packers for silos, and has for its object to provide a device of this character which embodies novel features of construction whereby the fodder can be quickly and thoroughly packed in the silo as it is placed therein.

A further object of the invention is to provide an ensilage packer which is comparatively simple and inexpensive in its construction, which can be readily mounted within a silo, which can be easily operated either manually or by means of a small engine, and which acts in a quick and effective manner to pack the fodder as it is placed in the silo.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:—

Figure 1 is a vertical sectional view through a silo provided with a roller ensilage packer constructed in accordance with the invention, portions thereof being broken away and shown in section. Fig. 2 is a top plan view of a silo provided with the roller ensilage packer, the roof of the silo being removed. Fig. 3 is a detail view of a portion of the sectional packer shaft, portions being broken away and shown in section to show more clearly one of the joints between the sections of the shaft. Fig. 4 is a detail view of one of the centering rollers carried by the shaft. Figs. 5 and 6 are detail views showing a modification in which tensioning means is provided for holding the rollers in proper engagement with the fodder.

Corresponding and like parts are referred to in the following description and indicated in all the views of the drawing by the same reference characters.

Referring to the drawings, the numeral 1 designates a silo which may be of any conventional construction, the roof thereof being omitted since it has no relation to the present invention. Extending across the top of the silo is a transverse beam 2 which carries a sprocket wheel 3. In the present instance this sprocket wheel is shown as arranged between the transverse beam 2 and a bracket 4 applied thereto, the hub 3a of the sprocket wheel being journaled within corresponding openings in the transverse beam and brace and being formed with a polygonal opening 5 through which the polygonal packer shaft 6 is passed. This shaft 6 is vertically disposed and extends centrally through the silo, the lower end of the shaft being provided with packing rollers 7 which are adapted to act upon the fodder to compress the same within the silo as the shaft 6 is rotated. These packing rollers 7 preferably have a substantially frusto-conical shape and project laterally from the lower end of the main shaft 6, the small ends of the rollers being formed with pivot pins 8 which engage bearings 9 projecting laterally from the lower end of the shaft 6, while the larger ends of the rollers are formed with pivot pins 10 which engage downwardly extending arms 11 carried by brackets 12 projecting radially from the shaft.

In order to keep the lower end of the main shaft 6 properly centered within the silo 1, arms 13 are provided which are arranged between the brackets 12 and are provided at the outer ends thereof with rollers 14 adapted to engage the interior walls of the silo 1. As the main shaft 6 is rotated the packing rollers 7 are caused to act upon the fodder below the same, and as the silo is gradually filled with fodder the rollers 7 rise, the polygonal main shaft 6 sliding upwardly through the sprocket wheel 3.

Arranged upon the exterior of the silo 1 is a shaft 15 which is journaled within suitable bearings 16. The upper end of this shaft is provided with a small sprocket

wheel 17 which engages a chain 18, said chain passing through suitable openings 19 in the side of the silo and also engaging the sprocket wheel 3 upon the transverse beam 2. The lower end of this shaft 15 is connected by the gearing 20 to a short shaft 21 journaled within a suitable bearing 22 and having a crank handle 24 applied thereto.

In the operation of the device, the silo is 10 gradually filled with fodder in the usual manner, the packing mechanism being operated so as to cause the rollers 7 to compress the fodder as it is placed in the silo. Any form of power may be utilized for 15 driving the packing mechanism, although in the present instance the device has been shown as constructed for manual operation. By turning the crank handle 24 motion is imparted to the shaft 15 on the out 20 side of the silo through the medium of the gearing 20, and from this shaft 15 motion is transmitted to the sprocket wheel 3 through the medium of the sprocket 17 and chain 18. The main shaft 6 is arranged to 25 rotate with the sprocket wheel 3 as well as to slide longitudinally through the axis thereof. As this shaft 6 is rotated the packing rollers 7 at the lower end thereof are moved around upon the fodder so as to 30 compress the same. As the fodder is placed in the silo and gradually fills the same the packing rollers 7 and shaft 6 rise, the upper end of the latter sliding freely through the sprocket wheel 3. As indicated more clearly 35 by Fig. 3, this shaft 6 is formed in a series of short sections which are detachably connected by suitable joints 25. As soon as one of the short shaft sections has been moved upwardly above the sprocket wheel 3, it is 40 detached and removed, so that the shaft does not interfere with the roof of the silo and is gradually shortened as the packing rollers rise within the silo and the sections of the shaft are successively removed.

45 A modification is shown by Figs. 5 and 6, in which the hub 3^a of the wheel 3 is provided at the top thereof with a pair of oppositely extending arms 30 and 31, the arm 30 being provided with an upstanding perforated guide lug 30^a, while the arm 31 is provided with a pair of perforated upstanding guide lugs 31^a. A Y shaped frame 32 which straddles the shaft 6 has the end thereof inserted in the perforated guide lug 30^a while the two arms thereof are in engagement with the lugs 31^a. A fixed roller 33 which engages one side of the shaft 6 is journaled between the two arms of the frame 32, while a movable roller 34 which 50 engages the opposite side of the shaft 6 is carried by a spindle 35 which slides within slots 36 formed in the arms of the frame 32. Suitable springs 37 are applied to the 55 arms of the frame and engage the spindle

35 to hold the roller 37 in a yielding engagement with the shaft 6, the tension in the said springs being adjustable by means of the nuts 38 which are threaded upon the arms of the frame 32 and against which the outer ends of the springs 37 abut. The 70 engagement of these rollers 33 and 37 with the shaft 6 serves to retard the sliding movement thereof so that the packing rollers 7 are always maintained in a proper engagement with the fodder.

Having thus described the invention, what I claim as new and desire to secure by Letters Patent, is:—

1. An ensilage packer for silos including an upright shaft arranged within the silo, 80 means for rotating the shaft, brackets projecting from the shaft, rollers upon the brackets for engaging the silo to maintain the shaft in a centered position therein, a second set of brackets projecting from the 85 shaft, and packing rollers journaled between the second set of brackets and the shaft.

2. An ensilage packer for silos including a sprocket wheel formed with a polygonal 90 opening, means for mounting the sprocket wheel at the upper end of a silo, means for driving the sprocket wheel, a polygonal shaft extending through the silo and slidably received within the polygonal opening of the sprocket wheel, said polygonal shaft being formed with short sections which have a detachable connection so that as the shaft moves upwardly the sections thereof above the sprocket wheel can be removed, brackets projecting laterally from the lower end of the shaft, rollers upon the brackets for engaging the interior of the silo to hold the shaft in a properly centered position therein, a second set of brackets 100 projecting from the lower end of the shaft, and packing rollers journaled between the second set of brackets and the shaft.

3. An ensilage packer for silos, including an upright shaft arranged within the 110 silo, brackets projecting from the shaft, rollers upon the brackets for engaging the silo to maintain the shaft in a centered position therein, a second set of brackets projecting from the shaft, packing rollers journaled between the second set of brackets and the shaft, a drive wheel having a central opening through which the shaft slidably passes, tensioning means upon the drive wheel for engaging the shaft, and means for 115 operating the drive wheel.

4. An ensilage packer for silos, including an upright polygonal shaft arranged within the silo, a packing roller at the lower end of the shaft, brackets projecting from the 120 shaft, rollers upon the brackets for engaging the silo to maintain the shaft in a properly centered position therein, a drive wheel

having a central polygonal opening through which the shaft slidably passes, means for driving said drive wheel, a fixed roller carried by the drive wheel and engaging one side of the shaft, a movable roller carried by the drive wheel and engaging the opposite side of the shaft, spring means for holding the movable roller in operative po-

sition, and means for adjusting the tension of the spring means.
